UNITED STATES PATENT OFFICE.

HENRY T. GERDES, OF LEBANON, PENNSYLVANIA, ASSIGNOR TO HAUCK MANUFACTURING COMPANY, OF BROOKLYN, NEW YORK, A CORPORATION OF NEW YORK.

FORGE.

Application filed June 14, 1927. Serial No. 198,745.

The invention relates to forges, fired with gaseous fuels such as gas or oil and preferably the latter. It relates more especially to a portable type of forge and which may

- 5 be self-contained, carrying with it a suitable storage tank for the fuel employed as well as means for affording air under pressure to atomize and mix the fuel and provide a blast of combustible mixture thereof.
- 10 The invention has for its object a device of this character which will afford an efficient heating chamber having an opening or mouth conveniently located for the insertion and removal of the objects or material
- 15 to be heated therein, for example, as rivets.

In carrying out the invention, a blast of the fuel mixed with the proper quantity of air is arranged to be directed into a specially constructed heating chamber so designed as 20 to further direct the now ignited blast downwardly upon the floor of the chamber and to cause it to be more or less retained thereover in eddies so that its velocity will be largely spent when it reaches the space immediately above the filling opening or mouth 25 of the forge. The working space in front of the same will then remain comparatively cool and accessible to the operator and thereby facilitate removal of the heated objects 30 in that the hand of an operator is able to approach very closely to the said opening without danger of burning. This effect is further enhanced by the deflection imparted to the outgoing stream of spent gases causing 35 the same to assume an upward direction and away from the front wall of the mouth portion of the heating chamber of the forge.

A further feature of the invention resides in a novel means for effecting the supply of 40 combustible fuel for use in the furnace.

The nature of the invention, however, will best be understood when described in connection with the accompanying drawings, in which:

- 45 Fig. 1 is a front elevation of the novel forge; and Fig. 2 is a side elevation thereof.

Fig. 3 is a part elevation of the opposite side of the forge and part vertical section of the heating chamber thereof.

- 50 Fig. 4 is a horizontal section through the heating chamber of the forge, taken on the line 4-4, Fig. 3, and looking in the direction of the arrows.

Fig. 5 is a part vertical section of an air motor employed to operate the fuel pump 55 as well as to supply at suitable pressure the air for atomizing and mixing the fuel.

Referring to the drawings, 10 designates a suitable supporting frame upon which the heating chamber and various related apparatus is supported, as well as the fuel tank 11 which may contain, for example, a supply of oil to be filled therein, when needed, through a suitable filling chamber 12 and fill pipe 13. A fuel supply pipe 14 dips into 60 the tank 11, extending substantially to the bottom thereof; and the same is connected with a pump 15 for supplying the fuel under 65 the desired pressure.

This pump is of any well-known rotary 70 type; and is actuated and operated in a novel manner as by being coupled, geared or belt-connected to the shaft 16 of an air motor 17. The latter, reference being had to Fig. 5, may be of any well-known or special type 75 and is preferably of the rotary impeller type as shown. Air for actuating said air motor 17 may be obtained from any suitable source as through the air supply pipe 18 having the control valve 19 included therein. When 80 the air is thus applied in opening the said valve, the air motor 17 will be rotated at comparatively high velocity and will correspondingly rotate pump 15 to supply the fuel to the burner member 20 through the 85 connection 21. Moreover, the exhaust from said motor 17 is directed through an outlet connection 22 communicating with said burner to atomize the fuel supplied thereto, 90 said air motor being designed in such a manner that the exhaust therefrom will be under sufficient pressure, say one-half pound to two pounds, to insure proper atomization of the fuel.

Burner 20 discharges through its nozzle 95 23 into the forge portion of the apparatus, which comprises a metal-bound casing of refractory material 25 having a tapered opening or throat 26 in the bottom thereof and substantially midway of the sides, said opening receiving the blast of combustible mixture from the nozzle, while in the wall opposite said inlet and substantially midway of the top and bottom of the casing the latter is provided with a flaring mouth 27 100 for receiving the articles to be heated as,

for example, the rivets 28, and constituting also an outlet for the spent gases or products of combustion.

Immediately adjacent the throat or inlet 26 is a baffle or wall 29, preferably inclined inwardly and more or less continuing the taper of the said throat. This wall or baffle extends across the rear of the casing and projects a short distance upwardly into the space constituting the heating chamber 30 of the said casing or forge portion, said baffle preventing also articles from reaching the inlet portions.

The roof or upper portion of said chamber, furthermore, is arched or curved substantially to a semi-cylindrical form, as indicated at 31, a wall 32 extending downwardly therefrom into the heating chamber to cooperate with the baffle 29 in imparting a rotary or whirling motion to the incoming blast of flame and directing the same to the bottom or hearth 33, as indicated by the arrows. Heating chamber 30 is constructed to be of suitable dimensions and is adapted to retain the articles 28 to be heated on the said hearth between said baffle 29 and a wall 34 at the front of the heating chamber and preferably inwardly inclined toward baffle 29, said wall together with the downwardly directed wall 32 determining the mouth or outlet 27.

The blast of fuel and flame thus directed over the hearth 33 is guided and more or less reversed upon itself by the inwardly inclined wall 34 to again pass over the said articles 28 and its energy is thus expended to a certain extent, reducing greatly the usual roar attendant upon the operation of this type of apparatus and insuring that in leaving the mouth 27 of the forge the gases will have but a minimum velocity so that the said mouth may be approached very closely in manipulating the article to be heated. The face 35 of the downwardly projecting wall 32 serves, also, and in addition to the roof 31, to reflect the heat downwardly upon the articles to further assist in bringing them to the proper temperature as rapidly as possible; and, if desired, a screen or guard member 36, carried by bracket arms 37 adjustably attached to the sides of the casing 25, as by the thumb nuts 38 and 39, serves to reflect back further portions of the heat as well as to screen appreciably an operator against the direct radiation from the interior of the forge. Sufficient space, however, is left upon either side of the said screen to admit of ready manipulation of the articles to be heated.

In this manner a very simple, effective and economically operated forge is provided, the heat developed by the combustion of the fuel being confined to a large extent to the vicinity of the hearth 33; and the said forge operates with a minimum of noise and also

admits of manipulation of the material to be heated with a minimum of discomfort to the operator.

I claim:

1. A forge comprising a casing of refractory material affording a heating chamber having an inlet tapered throat or opening through the bottom substantially midway of the sides thereof and a mouth opposite said throat to permit manipulation of material within the heating chamber, and a baffle adjacent the outlet of said throat continuing the taper of the same and extending across the rear of the casing and upwardly into the heating chamber thereof, the said chamber being provided with a reflecting surface between said baffle and mouth.

2. A forge comprising a casing of refractory material affording a heating chamber having an inlet throat or opening through the bottom thereof and a mouth opposite said throat to permit manipulation of material within the heating chamber, and a baffle adjacent the outlet of said throat, extending across the rear of the casing and upwardly into the heating chamber thereof and inclined inwardly, the said heating chamber being provided with a reflecting surface between the said baffle and the mouth of the heating chamber.

3. A forge comprising a casing of refractory material affording a heating chamber having an inlet throat or opening through the bottom and a mouth opposite said throat to permit manipulation of material within the heating chamber, and a baffle adjacent the outlet of said throat and extending across the rear of the casing and upwardly into the heating chamber thereof, said heating chamber being provided with a reflecting surface between the said baffle and the mouth of the heating chamber and including a wall member extending downwardly from the roof thereof with its under face affording a reflecting surface located over the bottom of said heating chamber.

4. A forge comprising a casing of refractory material affording a heating chamber having an inlet throat or opening through the bottom thereof and a mouth opposite said throat to permit manipulation of material within the heating chamber, a baffle adjacent the outlet of said throat, extending across the rear of the casing and upwardly into the heating chamber thereof and inclined inwardly, the said heating chamber being provided with a reflecting surface between the said baffle and the mouth of the heating chamber, the wall adjacent to the said mouth extending upwardly from the bottom of the heating chamber and directed inwardly.

5. A forge comprising a casing of refractory material affording a heating chamber having an inlet throat or opening through

the bottom thereof and a mouth opposite said throat to permit manipulation of material within the heating chamber, a baffle adjacent the outlet of said throat, extending 5 across the rear of the casing and upwardly into the heating chamber thereof and inclined inwardly, the said heating chamber being provided with a reflecting surface 10 between the said baffle and the mouth of the heating chamber, the wall adjacent to the

15 said mouth extending upwardly from the bottom of the heating chamber and directed inwardly and said reflecting surface including a wall member extending downwardly from the roof of the heating chamber between said baffle and inwardly inclined front wall.

In testimony whereof I affix my signature.

HENRY T. GERDES.
